UNITED STATES PATENT OFFICE.

THOMAS D. MOWLDs, OF BALA, PENNSYLVANIA.

FEED FOR STONE-CHANNELING MACHINES.

1,170,986.

Specification of Letters Patent.

Patented Feb. 8, 1916.

Application filed April 4, 1912. Serial No. 688,362.

To all whom it may concern:

Be it known that I, THOMAS D. MOWLDs, a citizen of the United States, residing at Bala, in the county of Montgomery and 5 State of Pennsylvania, have invented a certain new and useful Feed for Stone-Channeling Machines, of which the following is a specification.

The purpose of my invention is to provide 10 a rock channeling machine feed, preferably an auxiliary feed, in which the force moving the channeling tool laterally is applied close to the rock being cut.

A further purpose of my invention is to 15 provide automatic channel-wall-engaging feed at or near the bottom of a channeling frame or tool, preferably put into operation by the lateral feeding of the frame or tool.

A further purpose of my invention is to 20 use rolling means, preferably wheels to support the channeling frame from the bottom wall of the channel.

A further purpose of my invention is to 25 rotate a channeling tool by friction with the channel walls.

I have preferred to illustrate my invention by several forms thereof which I have determined to be practical, efficient and relatively inexpensive, and which at the same 30 time well illustrate the principles involved.

Figure 1 is a front elevation of a machine embodying one form of my invention. Fig. 2 is a section of Fig. 1 taken upon the line $w-w$ thereof. Fig. 3 is a section of the 35 structure shown in Fig. 1 taken upon the line $x-x$ thereof. Fig. 4 is a section of the structure shown in Fig. 1, taken upon the line $y-y$ thereof. Fig. 5 is a perspective view of a channeling tool used by me with 40 means applied, coöperating with the channel, to effect rotation of the tool. Fig. 6 is a broken section of the structure shown in Fig. 1, taken upon the line $z-z$ thereof. Fig. 7 is a central vertical section of a feed- 45 ing wheel illustrated in Fig. 1. Fig. 8 is a partial front elevation of a modified form of my invention. Fig. 9 is a section of the structure seen in Fig. 8, taken upon the line $w'-w'$ thereof. Fig. 10 is a broken section

corresponding to a part of Fig. 9 in partial 50 position within the channel.

Similar numerals of reference indicate like parts in the drawings.

My invention is applied to a channeling machine of the general character shown in 55 my Patent No. 1,012,569, of December 19, 1911. For simplicity I have shown a channel-entering frame having fewer channeling tools than are shown in my patent. Except for this omission and the addition of the 60 special feeding and rotating mechanisms, Figs. 1 and 8 herein correspond generally to Fig. 1 of said patent.

Upon any suitable coöperating supports, such as 1 and 2, I mount a frame 3, providing guides 4, 5 along which a frame 6 is adapted to be fed laterally by a cam upon or within cylinder 7, shown in the form of a cam slot which engages pin 8 upon the rear of the frame. In the illustration the 70 cylinder is mounted upon and rotated by shaft 9, which is rotated by sprocket wheel 10 and sprocket chain 11 from any suitable source of power. The connections which I prefer for this movement are those of my 75 patent above mentioned. Their exact character is not material to this invention.

Properly guided within the frame 6, I provide a vertically movable frame 12, which supports and carries channel cutting members 13, here shown as two in number, each of which may comprise a cutting tool 14 and a short rod 15, forming a part thereof or rigidly connected therewith. The frame 12 forms a carrier for the tool-carrying rods 80 and the tools themselves. Within a recess 16, generally alined with the guide for each of these cutting members, with this construction, I prefer to place a spring 17 engaging at one end with the frame and at the other 85 with a collar 18 upon tool rod 15. This construction is used to lift the tool slightly from the bottom of the channel between successive impact blows. This subject matter is not claimed here because it is claimed by 90 me in a co-pending application, Serial Number 554,687, filed April 11, 1910, issued May 27, 1913, as Patent No. 1,062,790.

In the form shown in Fig. 1, (the form making use of the short tool rod) I have intended but slight movement of the cutting members and have therefore disconnected them at 19 5 from the means for delivering the blow, here shown as a plunger 20. As in the case of my patent above mentioned, this plunger is driven downwardly by the re-action of a spring 21, compressed by the lifting action 10 of lugs 22 upon a collar 23. The lugs are operated by rotation of the member 24 through shaft 25, sprocket 26 and chain 27. I prefer to supply the movement to this 15 chain by the means shown in my patent above mentioned and have, therefore, not considered it necessary to illustrate this means here. The frame 12 is shown as capable of being lifted by the wheel 28 through gearing 29, 30, 31 and 32, engaging 20 a rack 33 upon the back of the frame 12. The weight of the frame tends to feed it downwardly. I have shown wheels 34, connected with the frame 12, which rest against the bottom of the channel and support the 25 weight of the frame. The reduced friction obtained by the rolling engagement of the wheels 34 with the bottom of the channel facilitates the lateral movement of the frame 6.

30 In existing channeling tools and machines, the movement of the tool has lagged somewhat behind the feed of the frame or carrier supporting the tool outside or above the cut. This tendency has been due 35 chiefly to the resistance of the stone to cutting by the tool, particularly as the end of the channel is approached, with the result that the tool tends to spring away from the cut toward the portion of the 40 channel just transversed, or, as it is termed, "refuse the cut". This takes up the lost motion in the intermediate mechanism and causes a lag corresponding to this lost motion. The lagging is increased through the 45 spring of the tool and shank or rod. With many channeling machines the lagging of the tool permitted by the spring of the tool rod is very great because of the length of unsupported drill rod presented.

50 Lost motion and spring have been greatly reduced in the machines of my Patent No. 1,012,569. Lost motion within the guides is still to be considered, since these guides cannot be fully tightened without undue interference with the feed. The lateral extent of the frame 12 cannot be increased much. Other means of reducing or eliminating the lag must, therefore, be supplied. I have provided feeding means within the 55 channel for this purpose. It operates at or near the bottom of the frame, against a wall of the channel to carry the frame, including the cutting members, along the channel.

60 While this invention is most useful with

machines of the character shown in my 65 patent aforesaid, it will obviously be capable of application to any channeling mechanisms in which a cutter frame, or tool support, extends down into the channel.

Various mechanisms for drawing or feeding 70 the lower part of the frame or cutting tool along the channel applied within the channel, will occur to the skilled mechanic, with the disclosure indicated above and contained herein. I have preferred to illustrate 75 but two of these many forms here. These are selected with a view to showing engagement with the bottom wall of the channel and engagement with the side or sides of the channel respectively. 80

In the form shown in Fig. 1, I have supported the weight of the frame 12 upon rotatable feed wheels 34 secured in extensions formed on the bottom of said frame and I have, preferably serrated or notched 85 them as at 35, in order that they may prick their way through the refuse in the bottom of the channel to the solid bottom. I prefer two disk-like wheels having a common axis, at each intended point of support, of general spool form, and shall consider the number as two hereafter for convenience. I 90 rotate the wheels 34 at such a speed that their peripheral speed shall equal or slightly exceed the lateral feed of the frame 95 6. Where they merely equal the lateral feed of the frame 6, any slip of the wheels 34 would result in corresponding lag and impose additional duty upon the frame 6 in dragging the wheels along the channel. 100 Where desirable, the wheels are given a slightly greater peripheral speed than the frame, so that any lag of the frame, due to interference with its feeding function, will be corrected by the accelerated feed of 105 the wheels. The peripheries of the wheels should be suitably tempered, so as to reduce wear. I have provided for the positive rotation of the wheels 34 by making them in general spool form, and driving them conveniently through a sprocket 36, between the two sides 37, chain 38 and sprocket 39. The sprocket 39 is shown as connected by shaft 40 with a gear 41 engaging the teeth 110 of a rack 42 upon any suitable member 43 of the head 44, which is movable vertically in agreement with the movement of the frame 12 and is supported in guides 45 within frame members 3. Other connection with a member parallel to the length of the channel, whether rigid or flexible, and at any preferred height could evidently be made in a great variety of forms. It will thus be seen that horizontal movement of the frame 12 will, with the particular illustration 115 selected, result in rotation of the gear 41 with corresponding rotation of both 120 sprocket wheels connected by the sprocket 125

chain, turning the wheels 34. The rate of peripheral speed of these wheels will obviously depend upon the relation between their effective diameter—determined by the 5 depth to which they sink into the bottom of the channel—and the pitch diameter of the wheel 41.

Various connected mechanisms, effecting, for example, the vertical movement of the 10 rods 20, guiding of the frame 12, the continuance of the connection between the driving mechanism and the heads 23, and the lateral feed, are fully explained in my Patent 1,012,569. They are not here elaborated because they are already matters of 15 public knowledge, through my patent, and the detail of their construction does not enter into the combinations intended to be claimed herein.

20 In the form shown in Figs. 8, 9 and 10, I serrate the peripheries of wheels 34, as in the other form, for the purpose of having them dig their way down to the bottom of the channel to keep the cutting members 25 uniformly at the proper depth, but do not, as in the other form, use them for positive lateral feeding purposes. They coöperate with the feeding mechanism in that the rolling support thus provided is effective in 30 reducing friction and rolling over or through obstructions at the bottom of the cut. In this form, at suitable points along the channel, I provide one or more friction wheels 46, which I prefer to taper as at 47 35 in order that they may guide their own way into the channel. I prefer to roughen these, as at 48, for feeding engagement with the side of the channel. I support them in any 40 suitable bearings, preferably giving them a slight yielding movement at the lower end, sidewise of the channel, as by springs 49, to press them against the channel wall. They then not only yieldingly engage the 45 wall to feed along the channel but also follow up breaks of the stone and other irregularities in the side wall of the channel and at all times bite into the side wall. These wheels 46 must be less in greatest 50 diameter than the width of the channel cut, in order that they may not at the same time, engage the channel on both sides. I arrange for the rotation of these wheels in the proper direction at a peripheral speed at least equal to and, for the reasons stated 55 before, sometimes slightly exceeding the lateral feed of the frame 6'; and do this by means of the properly guided shaft 50, suitably supported and limited against vertical movement by collar or collars 51. At any 60 suitable point I provide gear 52, engaging with rack 42', preferably upon the side of the head 44', since this location requires no intermediate gearing. The rigid connection shown here also offers some advantage over

flexible connections to cause this rotation. 65 It will be evident that my lateral feeding mechanism, in whichever form, is equally effective in feeding in both directions, that the feeding engagement is with a wall of the channel in each case, whether it be a 70 bottom or side wall thereof, and that it in each case is automatic both in its operation and in its reversal.

In Fig. 5, I have illustrated means for 75 rotating the cutting tool, which is put in operation automatically by engagement with a relatively fixed side member, preferably friction with the side wall of the channel. This, also, is automatic in its 80 feeding and in its operation when cutting in either direction. While I much prefer to apply this automatic turning to a tool having but slight vertical movement, being lifted little or none between impact blows, as illustrated in my co-pending application, 85 Serial No. 554,687, filed April 11, 1910, some of the advantage of my invention would be attained by connection of this tool-rotating mechanism with a full length plunger and connected tool, such as is shown in my 90 Patent 1,012,569. In either case I prefer to spline the feeding wheel 53 upon the tool carrying rod, as shown at 54, 55, so that the feeding wheel 53 may remain in bodily 95 fixed relation to the frame 12 or 12' and the tool carrying rod may slide within it for the intended movement or any slight accidental movement. In whichever form of my invention, I prefer not to rest the wheel 53 in too close proximity to the cutting edge, because it may slightly interfere 100 with the cutting operation, reducing the advantage of my invention; and for that reason I prefer to support this wheel above a tool rod bearing, as within the frame 12 105 or 12', which goes down into the channel. In either form, therefore, I prefer to mount the wheel 53 within a recess 56 in the frame, so as to prevent vertical movement with respect to the frame. I make the greatest 110 diameter of the wheel nearly equal to the effective width of the channel cut so that, while there will be no friction under ordinary circumstances, slight vibration of the rod or frame will bring the points 57 115 of the wheel into engagement with either side of the channel, though only one side at a time.

The teeth of the wheel are shown as of ratchet construction, as at 58, in order that 120 they may slip along the one side of the channel while engaging the opposite side during the lateral feeding of the frame along the length of the channel. It will be noted that the ratchet effect is reversed 125 with reversal of the direction of feed of the frame lengthwise of the channel, so that the rotation takes place in the same di-

rection at all times. Notwithstanding that the ratchet formation of the teeth will result in greater rotating tendency in one constant direction, whichever the direction 5 of frame feed along the channel, I prefer to prevent reverse turning by a drag operating against a disk or collar of any suitable character upon the same rod. This collar may correspond with the collar 18. The 10 drag 60 is preferably slight, by means of a spring engaging any character of roughened surface.

It will be evident that my feeding invention is broadly applicable to the feeding of 15 a channeling holder by means close to the tool and which may or may not engage with a wall of the channel, whether it be a side or a bottom wall.

It will be evident that any form of device 20 extending parallel with the length of the channel, might be engaged by the parts to cause the rotation desired, whether of the wheels 34, or 46, or of the tool. I prefer a rigid cross bar and rack for the horizontal member to any form of flexible construction 25 as the movement may be made more nearly positive.

I prefer making the feed of the tool from 30 within the channel automatic, through reaction due to the movement of the frame to any independent application of force for the rotation of the feeding wheels, supports, or members, as the construction is simplified and registration of the feeding impulse with 35 that given outside the cut (in auxiliary use of my feed) can more easily be insured in the automatic form than when a separate motive power is used.

It will be evident that my invention affords 40 practical, positive and effective means for auxiliary feed of a channeling frame or tool support along the channel itself which is automatic in its operation and, preferably, reversible.

Having thus described my invention, 45 what I claim as new and desire to secure by Letters Patent is:—

1. In a device of the character stated, a 50 channeling tool frame, a rotatable channeling-frame-support, adapted to engage the bottom of the channel, a channeling tool, and means for rotating the support, put in action by movement of the channeling tool frame along the length of the channel.

2. In a device of the character stated, a 55 channeling frame adapted to enter the channel, a rotatable frame support, engaging the bottom of the channel, and automatic means, set in operation by the moving of the frame along the length of the channel, for rotating the support.

3. In a device of the character stated, a 60 channeling frame, a tool carried by the frame, a rotary feed wheel entering the

channel and engaging a wall of the channel, 65 and means outside of the channel for rotating the wheel.

4. In a device of the character stated, a channeling frame, a channeling tool carried thereby, a combined frame support and 70 feeding wheel entering the channel, and means for turning the wheel to feed the tool carrying frame.

5. In a device of the character stated, a channeling frame, a rotatable member extended down into the channel, tool feeding means within the channel turned thereby and adapted to engage with a channel wall, a member parallel with the length of the channel in operative relation to the frame 80 and connections between the parallel member and rotatable member for causing rotation of the rotatable member by the movement of the rotatable member along the length of the channel.

6. In a device of the character stated, a channeling frame, a tool carried thereby and entering the channel and rotary means engaging a side of the channel to rotate the tool when the frame is fed along the channel 90 length.

7. In a device of the character stated, a channeling frame, a channeling tool therein, a tool rod for the tool, a wheel mounted upon the tool rod, adapted to engage a side 95 channel wall and rotate the rod, and means for preventing reverse rotation of the rod.

8. In a device of the character stated, a laterally movable channeling frame, a vertically movable frame guided therein, a channeling tool operating in the vertically movable frame; and a rotatable support for the vertically movable frame having an edge adapted to displace the refuse lying on the bottom of the channel and rest on the solid 105 stone.

9. In a device of the character stated, a laterally movable channeling frame, a vertically movable frame guided therein, a channeling tool operating in the vertically movable frame, a rotatable support for the vertically movable frame adapted to rest on the solid stone at the bottom of the cut and projections upon the portion of the support engaging the stone adapted to displace the 115 refuse lying on the bottom of the channel.

10. In a device of the character stated, a laterally movable channeling frame, a vertically movable frame guided therein, a channeling tool operating in the vertically movable frame, a rotatable support for the vertically movable frame adapted to rest on the solid stone at the bottom of the cut and having laterally spaced edges adapted to displace the refuse lying on the bottom of the 120 channel.

11. In a device of the character stated, a channeling frame, a laterally movable chan-

neling tool and rod supported thereby, rotary frictional side-wall-engaging means connected with the rod to cause rotation of the same with lateral movement of the rod and means for relatively increasing the frictional effect of engagement with one wall as compared with that of engagement with the other side wall of the channel.

12. In a device of the character stated, a channeling frame, a laterally movable recip-

rocating channeling tool and rod supported thereby and a ratchet wheel upon the rod engaging with a side wall of the channel to turn the rod in one direction with lateral movement of the rod along the length of the channel.
